UNITED STATES PATENT OFFICE.

BENNIE P. HANSON, OF EAGLE GROVE, IOWA.

ADJUSTABLE WAGON-TONGUE.

1,100,370.

Specification of Letters Patent. Patented June 16, 1914.

Application filed September 2, 1913. Serial No. 787,730.

To all whom it may concern:

Be it known that I, BENNIE P. HANSON, a citizen of the United States, residing at Eagle Grove, in the county of Wright and State of Iowa, have invented certain new and useful Improvements in Adjustable Wagon-Tongues; and I do hereby declare the following to be a full, clear, and exact description of the invention, such as will enable others skilled in the art to which it appertains to make and use the same.

This invention relates to wagon tongues, and one of the principal objects thereof is to provide a wagon tongue which may be attached to any wagon, said tongue embodying adjustable means whereby the tongue may be attached to wagons having hounds varying in width.

Another object of my invention is to provide means for securing a doubletree to the tongue, said means also serving the purpose of bracing the parts of the adjusting means.

Another object is to provide an adjustable tongue which is simple, very durable, efficient in operation, and which may be manufactured at small cost, and one which may be easily and quickly assembled or disassembled, and which may be quickly secured to the hounds of a wagon.

With these and other objects in view, the invention consists in the construction, combination and arrangement of parts herein-after more fully described and claimed, and illustrated in the accompanying drawings, in which like reference characters indicate like parts throughout the several views, and in which,

Figure 1, represents a top plan view of the tongue, showing the adjusting means secured thereto. Fig. 2, represents a sectional view on the line 2—2 of Fig. 1. Fig. 3, represents a sectional view on the line 3—3 of Fig. 1. Fig. 4, represents a top plan view of a portion of the tongue, the doubletree support being removed. Fig. 5, represents a bottom plan view of the stripped tongue.

Referring more particularly to the drawing, the tongue proper comprises a hollow tube 5, which is tapered from the rear to the front end thereof, and which is provided on its under side with the slot 6, running the entire length of the tongue. Near the rear end of tongue 5, is secured a pair of metal cross arms 7 and 8, said arms being positioned one above the other and secured

one to the upper and one to the lower face of said tongue by means of a bolt 9, the central portion of said arms being curved to conform to the periphery of said tongue, 60 and the ends of said arms extending at right angles to said tongue, said ends being spaced from each other throughout their length.

U-shaped clips 10, are secured adjacent the ends of arms 7 and 8, by means of bolts 11, and adapted to engage said clips are the rear inwardly bent ends of adjusting bars 12, said bars being secured in said clips by tightening the nut 13 on bolt 11, thereby drawing the ends of arms 7 and 8, together 70 and thus clamping said clips on said bars.

Forwardly of cross arms 7 and 8, a pair of angle irons 14, are secured to tongue 5, one on each side of the latter, the front portions of said angle irons being secured to 75 said tongue by means of bolts 15, the rear portions of said irons being bent outwardly from said tongue and have their rear ends doubled under to form spring clips 16. The front indent ends of bars 12, are adapted to 80 engage clips 16, and to be secured therein by means of bolts 17. For bracing irons 14, and also for forming a rest for a doubletree, I provide a substantially triangular shaped plate 18, which has offset flanges 19, formed 85 along its opposite edges, said flanges adapted to rest against the top faces of the outwardly bent portions of angle irons 14, and to be secured thereto by means of bolts 17 and bolts 20. The central portion of plate 90 18, is adapted to rest against the top surface of tongue 5, and is provided with an opening 21, for the reception of a pivot pin, said tongue being provided with an opening 22, adapted to register with opening 21. A 95 hammer strap 23, is secured to tongue 5, rearwardly to plate 18, and extends forwardly over said plate in spaced relation thereto, and has its forward end provided with an opening for the reception of said pivot pin, whereby a doubletree may be secured to the tongue.

It will be noticed that the plate 18, while serving as a rest for the doubletree, also serves as a brace for angle irons 14.

In attaching the tongue to a wagon, the bars 12 are placed one against each of the hounds, (not shown), a bar (not shown), is passed through said hounds and through openings 24, in said bars and tongue, for 110 securing the bars to the hounds.

In adjusting my tongue with wagons hav-

ing hounds of varying widths, all it is necessary to do is to loosen the nuts on bolts 11 and 17, whereby the space between the bars 12, may be adjusted at will, and said bolts 5 may then be tightened, securely holding said bars in adjusted position.

Although I have described the preferred embodiment of my invention, I may make such changes in the construction, combination 10 and arrangement of parts as do not depart from the spirit of the invention and the scope of the appended claims.

Having thus fully described my invention, what I claim as new and desire to set 15 cure by Letters-Patent is,

1. A vehicle tongue comprising a tube, arms secured thereto, one above the other, said arms spaced from each other, angle irons secured to said tube and diverging in 20 opposite directions therefrom, side bars, means for clamping said side bars to said arms, the rear ends of said angle irons being doubled under and adapted to clamp said side bars, and a plate adapted to brace said 25 angle irons and to afford a rest for a double-tree.
2. A vehicle tongue comprising a tube,

cross arms secured thereto on opposite sides thereof, said arms being spaced from each other, U-shaped clips secured to said arms 30 on the outer ends thereof, side bars having inbent front and rear ends, the rear ends of said side bars adapted to engage said U-shaped clips, bolts passing through said arms and clips, whereby the rear ends of 35 said side bars may be clamped in said clips, angle irons secured to said tube and diverging oppositely therefrom, the rear ends of said angle irons being turned under, the front inbent ends of said side bars adapted 40 to engage said under turned ends, bolts adapted to pass through said angle irons and under turned ends for clamping the front inturned ends of said side bars, and a plate adapted to be secured to said angle 45 irons for bracing the same, said plate affording a rest for a double-tree.

In testimony whereof I have signed my name to this specification in the presence of two subscribing witnesses.

BENNIE P. HANSON.
